UNITED STATES PATENT OFFICE.

JACOB D. SCHAKEL AND JOSEPH RICE, OF CHICAGO, ILLINOIS, ASSIGNEES TO ELEVATOR COMPANY OF AMERICA, OF CHICAGO, ILLINOIS.

ELECTRIC AUTOMATIC DOOR-LOCKING SYSTEM.

Application filed January 3, 1922. Serial No. 526,752.

To all whom it may concern:

Be it known that we, JACOB D. SCHAKEL and JOSEPH RICE, citizens of the United States, residing at Chicago, in the county of Cook and State of Illinois, have invented a certain new and useful Improvement in Electric Automatic Door-Locking Systems, of which the following is a full, clear, concise, and exact description, reference being 10 had to the accompanying drawings, forming a part of this specification.

Our invention relates to automatic door locking systems for elevators, and more particularly to a door locking system whereby 15 the doors cannot be opened except when the elevator car is stopped opposite the floor at which the door mechanism is operated. Ordinarily in automatically operated elevators it is possible when a car is passing a 20 floor to operate the lock to open the door by pressure on the locking member all of the time that the car is approaching the floor, so that when the car reaches the proper position relative to the floor, the door can 25 be forced open, thus stopping the elevator. This is particularly objectionable in an elevator of this type as it makes it possible for one person to take possession of the elevator car after another person has operated the 30 push button to bring the elevator to the floor at which this person is waiting, thus preventing the person operating the push button from obtaining the elevator car for his use, and in that way preventing the proper 35 operation of an automatically operated elevator system.

Our invention has for its purpose to provide a system for locking the doors of an elevator enclosure at the various floors, 40 whereby said doors cannot be opened except when the elevator car is stationary and when the elevator car is opposite the floor. As the elevator car will only stop opposite a floor when the automatic elevator control mechanism is actuated by means of the push button at the floor, the elevator car can only be obtained by the person who has pushed the button, thus preventing others from obtaining the use of the car by taking it away from 45 the person who should have obtained the use of the same by pushing the button.

It is a purpose of the invention to provide an electrically operated lock of this character which is so constructed that no current 50 passes through the electromagnet-coils of the

lock, except when the lock is being operated and the door is still closed, it being particularly a purpose of the invention to prevent the dissipation of the electrical current due to energizing the coils of the electric door lock when this is unnecessary, thus there is no current passing through the same when the door is open, and also no current passing through the lock when a door is closed, except while the lock is being operated by 60 operating either the knob on a swinging door or the catch on a sliding door.

It is a further purpose of the invention to provide a door locking system for automatically operable elevators which comprises 70 a source of current independent of the current for operating the car, and to provide switching means in the conductors leading from said source to the electric lock comprising a switch which is so constructed that the 75 same will be open while the elevator car is in motion, but which will be closed when the elevator car is not in motion. This contact may be operated by means of an electromagnet which is energized by the current used 80 for operating the elevator car, or which is controlled by means of any desirable part on the control mechanism for the elevator or the driving mechanism therefor.

It is a further purpose of the invention to provide the conductors extending from the source of current mentioned above with a switch mechanism which is normally open but which is closed in any desired manner 85 when the elevator car is opposite a floor or landing, and to provide for a normally open switch mechanism in said conductors between said source of current and said electric lock which is closed by the actuation of the handle on the door in the case of a sliding door, or the knob on the door in the case of a swinging door, thus providing an electrically operated lock which will only be 90 operated by the electric current passing through the same when the car is not in motion, when the car is opposite a landing or floor, and when the door at said floor or landing is being operated to open the same.

It is still a further purpose of the invention to provide an additional switch mechanism in 100 the case of a swinging door, which is closed while the door is closed, but which opens as soon as the door is opened so as to break the circuit as soon as the door is opened to prevent the unnecessary use of the electric cur- 105 110

rent after the door has been unlocked. In the case of a sliding door the contact is broken by the physical opening of the door thus making it unnecessary to provide an additional switching member as in the case of the swinging door.

It is also an object of the invention to provide manually operated means for unlocking the door in either case, in case of emergency 10 said manually operated means preferably comprising a member which may be operated from the interior of the hatch by means of a handle member which is normally in operative position, and which may be unlocked from the outer side of the hatch by means of a key member. In the present instance the key member used is the handle which is ordinarily in position on the inner side of the lock, said handle being made detachable.

Other objects and advantages of our invention will appear as the description of the accompanying drawings proceeds. However, we desire to have it distinctly understood that we do not intend to limit ourselves to the exact details shown and described, but that we intend to include as part of our invention all such obvious changes and modifications of parts as would occur to a person skilled in this art, and as would fall within the scope of the claims.

In the drawings:

Fig. 1 is a side elevation of our improved locking mechanism for an automatically operating elevator door with the cover plate thereof removed;

Fig. 2 is a transverse sectional view thereof showing the same applied to an elevator door, said section being taken on the line 2—2 of Fig. 1;

Fig. 3 is an end view of the mechanism shown in Fig. 1 showing the portion thereof secured to the hatch;

Fig. 4 is a similar view of the portion 45 of the locking mechanism secured to the door showing a portion of a swinging door in cross section;

Fig. 5 is a view similar to Fig. 1 of a modified form of locking mechanism such 50 as used on a sliding door;

Fig. 6 is a diagram showing the arrangement of the electrical circuit for the form of the device shown in Fig. 1; and

Fig. 7 is a similar view of the electrical circuit used for the form of the device 55 shown in Fig. 5.

Referring in detail to the drawings, the improved lock used in the locking system described above comprises a casing 10 which is secured to the door by any suitable securing devices passing through the perforated ears 11 and a casing member 12 which is secured to the hatch at the doorway by any suitable fastening means passed through 60 the perforated ears 13. The member 10 is

provided with end walls 14 and 15, the end wall 15 being provided with openings through which the slideable bolts 16 and 16' are adapted to slide. The member 10 is also provided with an inwardly extending lug 17 which is provided with a constricted portion at 18 which passes through a slot 19 provided in the member 16 and with a similar lug 17' which is provided with a constricted end portion 18' 75 which passes through a slot 19' in the bolt 16'. A finger 20 extends into the slot 19 from the main portion of the bolt 16, and a finger 20' extends into the slot 19' from the main portion of the bolt 16'. Coiled around said fingers 20 and 20' are the springs 21 and 21' which extend from the end walls 22 and 22' of the slots 19 and 19' to the lugs 18 and 18'. The inner end portions of the bolts 16 and 16' are bifurcated so as to provide the legs 23 and 24 and 23' and 24' respectively. The extreme end portions of the legs 23 and 24 and 23' and 24' are bent at right angles to the length thereof to provide the laterally extending lugs 25 and 26 and 25' and 26' respectively.

Mounted in the casing member 10 are the shafts 27 and 27' which are square in cross section, the member 27 having the knobs 28 and 28' mounted on a square end portion thereof and being provided with a sleeve 29 which is provided with a pair of fingers 30 and 31 projecting laterally therefrom which are adapted to engage 100 with the members 25 and 26 to move the bolt toward the right in Fig. 1. The shaft 27' is provided with a similar collar 29' having the lugs 30' and 31' thereon, which are adapted to slide the bolts 16' to the 105 right in a similar manner to the manner in which the bolt 16 is moved by actuation of the knobs 28 or 28'. The casing member 12 is provided with an end wall 32 which has a block of insulating material 110 33 mounted thereon, said block of insulating material being provided with stationary conductor strips 34, 35 and 36, the strips 34 and 35 being provided with the right angularly bent end portions 37 and 38 115 which form stationary contacts which are adapted to be engaged by the contact member 39 provided on the end of the slideable bolt 40 which has the block 41 mounted on the end thereof, said block 41 being adapted 120 to be engaged by the bolt 16 to hold the same in the position shown in Fig. 1, when the door is closed. The block 41 is slidably mounted in an opening 42 in the end wall 43 of the casing 12 that faces the 125 door.

Mounted between the block 41 and the partition 44 is a coil spring 45 which is under compression when the parts are in the position shown in Fig. 1 and which 130

tends to force the block 41 toward the right in Fig. 1, so that when the knob is turned so as to withdraw the bolt 16, the block 41 will move to such position that the contact 39 will engage with the contacts 37 and 38 due to the compression of the spring 45. The spring 45, however, is weaker than the spring 21 so that when the operator lets go of the door knob the spring 21 will 10 force the bolt 16 into engagement with the block 41 and force said block 41 to substantially the position shown in Fig. 1, so as to break the contact between the members 37 and 38 and the member 39.

15 It will be seen that when the door 46 shown diagrammatically in Fig. 6 is opened by turning on the hinges, the bolt 16 will be out of alignment with the block 41 and the spring 45 will hold the contact 39 in 20 engagement with the contacts 37 and 38. The switch formed by said contacts will accordingly be open when the door is closed and closed when released by turning the knob, remaining closed while the door is 25 open. The strip 36 and the end of the strip 35 opposite the contact 38 are provided with curved hook-like contact members 47 and 48. Cooperating with said contacts is a sliding contact member 49 which 30 is provided with a bolt-like end portion 50 which is adapted to project outwardly beyond the end wall 43 of the casing 12 due to the action of the coil springs 51 mounted between the partition 44 and the enlarged 35 portion of the bolt.

It will be seen that when the door is closed, the member 50 will be in engagement with the end wall 15 of the casing 10 and the contact 49 will close the circuit 40 between the fingers 47 and 48. However, when the door is swung open the support for the bolt 50 is removed and the spring 51 will move the same toward the right in Fig. 1, so as to break the engagement between the contacts 47 and 48 and the movable contact 49.

It will be seen that when the door is opened the switch formed by the contacts 47, 48 and 49 will be open due to the action 50 of the movable contact 49 described above, but that when the door is closed the contact will be held in the position shown in Fig. 1, due to the engagement of the wall 15 with the bolt 50.

55 Mounted in the upper part of the casing 12 are the solenoids 52 of an electromagnet and the armature 53 cooperating therewith which is mounted pivotally between the ears 54, as will be clear from Fig. 1. A spring 55 is provided for holding the armature 53 spaced from the pole piece 56 of the electromagnet when the electromagnet is not being energized, and a finger 57 is provided on said armature 53 which engages the end 60 wall 32 of the casing to limit the movement

of the armature toward said end wall and hold the same in such position that it is capable of being attracted by the electromagnet. The armature 53 is adapted to engage with the finger 58 projecting laterally 70 from the lever 59, which is pivotally mounted on the pivot member 60, and which is provided with a stop member 61 having a ledge 62 thereon adapted to receive the right angular end portion 63 of the link 64 pivoted at 65 in the casing 12 and pivotally secured at 66 to the link 67 which is pivoted at one end thereof by means of the pivot pin 68 to the bolt member 69, which is provided with a beveled end portion 70, as is 80 customary with bolts on doors.

It will be seen that when the member 61 is in engagement with the end of the link 64, the joint at 66 cannot be broken due to the fact that the link 64 cannot be swung out 85 of the position shown in Fig. 2, the member 67 being pivotally connected with the member 64 intermediate the ends of said member 67. Accordingly when the parts are in the position shown in Fig. 2, the door cannot be opened due to the engagement of the member 70 with the bolt 16'. However, if the solenoids 52 are energized the armature 53 will be attracted and the end thereof 90 will engage with the pin 58 throwing the member 61 around in a counterclockwise direction in Fig. 2, so as to cause the member 61 to disengage from the member 64. When a pull on the door is then exerted the bolt 16' will swing the cooperating bolt 69 100 around the pivot 71 against the tension of the spring 72, which extends around the pivot 71 at one end thereof and engages with the bolt 69 at said end and extends around the pin 73 at the other end thereof. As soon as the door is opened the member 69 is swung back to the position shown in Fig. 2 due to the action of the spring 71, and as soon 105 as the solenoids 52 are de-energized the parts will return to the position shown in Figs. 1 and 2. The bolt 16' being spring pressed will ride over the inclined surface 74 when moving in the opposite direction until it passes the end portion of the hook-like portion 70, after which it drops back of the shoulder 75 to again lock the door.

110 It may at times be desirable or necessary to open the door manually, and for this reason the operating mechanism comprising the squared shaft 27' is provided. The shaft 120 27' is provided with a squared opening 76 in which the end portion 77 of the detachable operating handle 78 is mounted. The handle 78 is in the form of a key-like member, and is adapted to turn the shaft 27' so 125 as to withdraw the bolt 16' when desired. The member 78 is provided on the inner side of the door, and should it be desired to operate the door from the outside thereof, the key 78 may be removed from the inside 130

and may be used on the outer side of the door for opening the same. The shaft 27' is provided with the opening 76 which extends from end to end thereof, and has a block 79 mounted therein. Mounted in the block 79 is a pin 80 about which is coiled the compression spring 81. The pin 80 is slidably mounted in the member 79 and is provided with a block 82 square in cross section, which is adapted to close the opening 83 in the circular plate 84, so as to give a neat appearance to the outer side of the casing. If it is desired to unlock the door from the outside manually, all that is necessary is to embody the square end portion 77 of the key 78 into the opening 83 by pushing the block 82 whereupon the spring 85 is compressed so as to allow the square end portion 77 to enter the opening 83. The lever 59 is normally held in the position shown in Fig. 2 by means of the spring 85 which is hooked over the member 59, as will be clear from Fig. 2, at one end thereof and which extends around the finger 73 at the other end thereof.

Referring now to Fig. 6 the locking system comprises a source of electric current, such as the battery 86, which may be a storage battery or any other suitable source of current, from which the conductors 87 and 88 extend. The conductor 88 extends from the battery 86 to a contact member 89, which together with the contact 90, forms the stationary contacts of a switching mechanism comprising the movable contact member 91. Extending from the contact 90 to the conducting strip 37 is the conductor 91 and from the conducting strip 36 the conductor 93 extends to the solenoids 52. From said solenoids the conductor 94 extends to the stationary contact 95 which cooperates with the movable contact 96, said movable contact 96 being adapted to simultaneously engage with the contact 95 and the contact 97 at one end of the conductor 87. The switch 91 is operated by means of an electromagnet, which is energized by the current used in operating the elevator car so as to keep the switch open, or in any other suitable manner by means of any part of the controlling mechanism for the elevator. Said switch member 91 is held out of engagement with the stationary contacts 89 and 90 when the elevator car is in motion by said electromagnetic means and is closed when the car is not in motion, in any suitable manner, such as by the action of gravity. The switch, comprising the members 95, 96 and 97, is operated by means of a stationary cam 98 on the elevator car, which is adapted to engage with a roller 99 on the end of a link 100 which is pivoted at 101 on any suitable support, and which carries the contact 96 at the end thereof. When the cam 98 engages with the roller 99 the parts are

moved into the position shown in Fig. 6 so that the contact 96 closes the gap between the contacts 95 and 97. Accordingly when the car is stopped, the contact 91 will move to circuit closing position. The contact 96 will move to circuit closing position when the car is stopped opposite the floor, as the rollers 99 are located in such positions in the elevator shaft that the cams 98 will engage therewith only when opposite a floor 75 and the contact 39 will be in circuit closing position when the door is being opened by turning the knob, while the contact 49 will be in circuit closing position until the door has been moved in opening the same 80 to such position that the same no longer holds the contact 49 in engagement with the contacts cooperating therewith. Accordingly, when the knob 28 is turned and the car is stationary and opposite a floor, 85 the solenoids 52 will be energized to operate the electric lock to unlock the toggle comprising the link 64 and the link 67, so that the door can be swung open. As soon as the door is swung open, however, the circuit is broken, due to the fact that the contact 49 moves out of engagement with its cooperating contact as previously explained, as soon as the door is swung open. This is particularly advantageous, as in this manner the 90 dissipation of the electrical energy from the battery 86 is prevented through the circuit described above should the door be left open and the elevator remain at a floor for a long 95 period of time, the other contacts being still 100 closed due to the fact that the elevator is stationary and at a floor.

In Fig. 5 is shown a form of lock which is used with a sliding door, said lock comprising a member 10' mounted on the door and having ears 11' for securing the same to said door and a member 12' which is adapted to be secured to the hatch by means of securing means passed through the ears 13'. Slidably mounted in the member 10' is a 110 bolt 102 which passes through the guide member 103 and which is pivoted at 104 to the link 105, which link is pivoted at 106 to the arm 107 of the lever 108, which lever is pivoted at 109 in the member 10'. The 115 opposite arm 110 of the lever 108 is provided with a rib 111 which is adapted to be engaged by the fingers when passed through the opening 112 in the member 10'. Coiled about a stud 113 is a spring 114 having the end portion 115 engaging with the end wall of the casing and having the end portion 116 engaging with the rib 111.

The member 108 is also provided with an arm 117 projecting forwardly from the same 125 and having a head 118 thereon which is adapted to engage with the block 119 to limit the movement of the lever in a counterclockwise direction, so that the same will not move further in a counterclock- 130

wise direction than the position shown in Fig. 5 when the bolt 102 will be drawn inside the casing 10'. The spring 114 is put under compression when the arm 110 of the lever is moved toward the right in Fig. 5, so that said spring will tend to retract the bolt 102 when the lever is released. Arranged opposite the bolt 102 in the member 12' is a sliding block 120 which is provided with a flange 121 adapted to engage the shoulder 122 to limit the outward movement of the block, and which has the pin 123 secured thereto, said pin 123 extending through the inwardly extending flange or partition 124 and being provided with a compression spring 125 coiled about the same between said flange 124 and the flange 121, so that when said block 120 and the pin 123 are moved toward the left in Fig. 5, the spring will be put under compression so as to again return the parts to the position shown in Fig. 5 when the pressure on the block 120 is removed. The block of insulating material 126 is provided with a pair of contact members 127 and 128 which are provided with hook-shaped end portions, said end portions being adapted to be engaged by the end of the member 123 when said member is moved toward the left in Fig. 5. Such action will take place when the handle 111 is moved toward the right in Fig. 5 due to the fact that the bolt 102 will be projected into engagement with the block 120. However, as soon as the handle is released, the spring 114 will return the parts to the position shown in Fig. 5, and the spring 125 will return the bolt or pin 123 to the position shown in Fig. 5, thus breaking the contact between the members 127 and 128 and said pin or bolt.

Referring now to Fig. 7 in which is shown a sliding door 129, which sliding door is provided with the casing 10' carrying the actuating parts described above, the contact members 127 and 128 are shown with the co-operating contact 123, which is actuated in the manner described above. The circuit shown in Fig. 7 is quite similar to that shown in Fig. 6, except that only one switching device comprising the members 127, 128 and 123 is used at the door instead of two switching devices as shown in Fig. 6. The switching devices comprising the contacts 95, 96 and 97 and the contacts 89, 90 and 91 and the conductors leading therefrom to the battery 86 and to the electrical door lock comprising the solenoids 52 are of the same construction as those shown in Fig. 6, the same numerals being used for said parts as in Fig. 6. The electrically operated lock is constructed of the same component parts as the lock shown in Fig. 1, but the parts are arranged in a slightly different manner due to the different structure of the door. The same numerals are applied to these parts as

in Fig. 1, and the operation thereof will be readily understood by referring to the description thereof in connection with Figs. 1 and 2. The hook-like end portion 70 of the member 69 engages with a hook-like member 130 on the end of the pivot arm 131, said arm 131 being pivoted in the casing 10' at 132 and having a spring 133 secured thereto by hooking the same over said arm at 134, the opposite end of said spring engaging 75 with the upper wall 135 of the casing 10', whereby the spring 133 will tend to turn the member 131 in a counterclockwise direction in Fig. 5, so as to hold the members 70 and 130 in engagement. A shaft 136 is journaled in the member 10' and is provided with an arm 137 extending laterally therefrom, which has a ledge 138 at the end thereof which is adapted to engage with the underside of the arm 131 when the shaft is rotated in a clockwise direction. Said shaft 136 is adapted to be rotated by a key similar to the key 78, and is provided for the purpose of manually unlocking the lock when the supply of current fails, or when 80 for any other reason it may be necessary to unlock the door without the use of the automatic locking device. A stop lug 139 is provided on the cross member 140 in the casing 10' to limit the counterclockwise movement of the arm 137 and shaft 136.

It will be seen that in the system shown diagrammatically in Fig. 7, no current will pass through the solenoids 52 to unlock the electrical lock, except when the switch comprising the contacts 89, 90 and 91 is closed, which will only be closed when the elevator car operating current is off, and when the switch comprising the contacts 95, 96 and 97 is closed, which will only take place when 90 the elevator car is opposite a floor, and when the handle is being actuated on the door to open the same, as it will only be at that time that the contact 123 will engage with the contacts 127 and 128 to close the circuit. When all the above mentioned contacts are closed, the armature 53 will be attracted by the electromagnet comprising the solenoid 52 and will engage with the finger 58 throwing the member 61 out of engagement 100 with the shoulder 63, whereupon the member 69 will drop downwardly so as to release the catch 130 from the catch 70, when the door is pulled to the right. As the door 129 is slid open the member 10' will move away from the member 12' and the member 102 will move out of engagement with the member 120, thus the pin 123 will move to the right in Fig. 5, and the contact will be broken between the pin 123 and the members 127 and 128 thus breaking the circuit. Accordingly there will be no current passing through the solenoid 52 in Fig. 7 when the door is open, nor when the door is closed, except while the handle is being actuated 110

120

125

130

by pressing on the same against the tension of the spring 114. It will thus be seen that the current from any suitable source, such as the battery 86, will not be dissipated due to passing through the solenoid 52 when the door is left open in a similar manner to that described in connection with Fig. 6. It is, of course, to be understood that the members 40, 41, 49, 50, 120 and 121 are insulated from the casings 12 and 12' respectively in any desired manner.

Having thus described our invention, what we desire to claim and secure by U. S. Letters Patent is:

- 15 1. A door locking system of the character described comprising a door, an electrically operated lock for said door, a source of electric current, conductors leading from said source of current to said lock and switching means interposed between said lock and said source of current, said switching means comprising a manually operable member independent of said lock for closing said circuit.
- 20 2. A door locking system for elevators comprising a door, a lock for said door, electrically operated means for releasing said lock to unlock said door, a source of electric current, conductors leading from said source of current to said lock and switching means interposed between said lock and said source of current, said switching means mechanically closing said circuit when the elevator car is opposite a floor due 25 to the position of the car.
3. A door locking system for elevators comprising a door, an electrically operated lock for said door, a source of electric current, conductors leading from said source of current to said lock and switching means interposed between said lock and said source of current, said switching means closing said circuit when the elevator car is stopped to operate said lock to unlock said door.
- 40 4. A door locking system for elevators comprising a door, a lock for said door, electrically operated means for releasing said lock to unlock said door, a source of electric current, conductors leading from said source of current to said lock and switching means interposed between said lock and said source of current, said switching means closing said circuit to unlock said door when the elevator car is stopped 45 opposite a floor.
5. A door locking system for elevators comprising a door, an electrically operated lock for said door, a source of electric current, conductors leading from said source of current to said lock and manually operable switching means independent of said lock interposed between said lock and said source of current, said switching means closing said circuit when actuated and the elevator car is stopped opposite a floor.

6. A locking system for elevator doors comprising a lock electrically operated to unlock the same, a source of current and control means interposed between said lock and source of current, said means comprising switching mechanism controlled by the position of the elevator car, switching mechanism controlled by the controlling mechanism of said elevator car and manually operated switching mechanism. 70 75

7. A locking system for elevator doors comprising an electrically operated lock, a source of current and control means interposed between said lock and source of current, said means comprising switching 80 mechanism operated by a member on and controlled by the position of the elevator car, switching mechanism controlled by the controlling mechanism of said elevator car and switching mechanism controlled by the 85 position of said door.

8. A locking system for elevator doors comprising a lock electrically operated to unlock the same, a source of current and control means interposed between said lock 90 and source of current, said means comprising switching mechanism controlled by the position of the elevator car, switching mechanism controlled by the controlling mechanism of said elevator car and manually operated switching mechanism, said lock being provided with a manually operated emergency unlocking device. 95

9. In a locking system of the character described, the combination with an electrically operated lock of means for operating 100 said lock comprising a switching device carried by the elevator enclosure, and operating means for said switching device carried by the elevator door, comprising a manually 105 operable independent member adapted to engage with a movable portion of said switching device.

10. In a locking system of the character described, the combination with an electrically operated lock of means for operating 110 said lock comprising a switching device carried by the elevator enclosure, and operating means for said switching device carried by the elevator door comprising a member 115 adapted to engage with a movable portion of said switching device movable into circuit closing position upon manual actuation of said operating means, said operating means being independent of said lock. 120

11. In a locking system of the character described, the combination with an electrically operated lock of means for operating said lock comprising a switching device carried by the elevator enclosure comprising a 125 pair of stationary contact members, and a movable contact member cooperating therewith and operating means for said switching device carried by the elevator door, said movable contact being movable into circuit 130

closing position upon manual actuation of said operating means, said operating means being provided with means for retracting the same upon release thereof, said operating means being independent of said lock.

12. In a locking system of the character described, the combination with an electrically operated lock of means for operating said lock comprising a switching device carried by the elevator enclosure, and operating means for said switching device carried by the elevator door comprising a member adapted to engage with a movable portion of said switching device, and manually operable means for unlocking said door independently of said electric lock.

13. In a locking system of the character described, an elevator enclosure, a door, a latch for said door, an electrically operated device for unlocking said latch and a switching device for operating said unlocking device, comprising a manually operable member on said door independent of said latch.

14. In a locking system of the character described, an elevator enclosure, a door, a latch for said door, an electrically operated device for unlocking said latch and a switching device for operating said unlocking device, comprising a manually operable member on said door independent of said latch.

and a mechanically operable switch member operated by the position of the elevator.

15. In a locking device for elevators, an elevator enclosure, a door, means for locking said door comprising interengaging members on said door and said enclosure, the member on said enclosure being swingable out of engagement with the member on said door upon opening movement of said door, means for normally holding said member from swinging when said door is closed, electrically operated means for releasing said holding means and a switch for operating said electrically operated means.

16. In a locking device for elevators, an elevator enclosure, a door, means for locking said door comprising a catch on said enclosure adapted to engage means on the door to hold said door against opening, said catch being adapted to move out of locking position by an opening movement of said door, means for normally holding said catch in door locking position, electrically operated means for releasing said catch to unlock said door, and a switch for operating said electrically operated means.

In witness whereof, we hereunto subscribe our names this 20th day of December A. D., 1921.

JACOB D. SCHAKEL.
JOSEPH RICE.
